[57] CLAIM

The ornamental design for a building structure, substantially as shown.

DESCRIPTION

FIG. 1 is a view in perspective of a building structure according to my invention, and representing a view of what may form the front/side, or rear/side, or vice versa, of such building structure, but which for ease of description will be designated as a front/side view.

FIG. 2 is a rear view in perspective, taken in the opposite direction from FIG. 1.

FIG. 3 is a front elevation view of the building structure of FIG. 1, according to the illustrative convention adopted for FIG. 1.

FIG. 4 is a plan view of the building structure of FIG. 1. FIG. 5 is a rear elevation view of the building structure of FIG. 1.

FIG. 6 is a side elevation view of the building structure of FIG. 1.

FIG.1

FIG. 2
